UNITED STATES PATENT OFFICE.

FRANK E. WILLEY, OF CLAREMONT, NEW HAMPSHIRE, ASSIGNOR TO SULLIVAN MACHINERY COMPANY, A CORPORATION OF MASSACHUSETTS.

ELECTRIC FUSE.

1,393,281.

Specification of Letters Patent. Patented Oct. 11, 1921.

Application filed November 16, 1916. Serial No. 131,690.

To all whom it may concern:

Be it known that I, FRANK E. WILLEY, a citizen of the United States, residing at Claremont, in the county of Sullivan and State of New Hampshire, have invented certain new and useful Improvements in Electric Fuses, of which the following is a full, clear, and exact specification.

My invention relates to electric fuses.

10 It has for its object to provide an improved fuse in which the parts are readily separable and wherein the fuse carrying element forms a unit which, while normally held against longitudinal or rotary movement relative to its casing, may be readily removed therefrom when desired. A further object of my invention is to provide an improved fuse wherein the fusible element is effectually inclosed in such a manner that the rupture thereof occurs between relatively close walls of insulating material, and wherein the interior of the fuse casing is also preferably automatically cleaned by the removal of the fuse carrying element therefrom. These and other objects of my improved construction will, however, hereinafter more fully appear.

In the accompanying drawings, I have, for purposes of illustration, shown one embodiment which my invention may assume in practice.

In these drawings,—

Figure 1 is a longitudinal horizontal sectional view of the fuse carrying element and casing carried in its supports.

Fig. 2 is a longitudinal vertical sectional view of the fuse casing and removable fuse carrying element when separated.

Fig. 3 is a side elevation of the fuse carrying element.

Fig. 4 is a transverse sectional view on line 4—4 of Fig. 1.

Fig. 5 is a transverse sectional view on line 5—5 of Fig. 2.

45 In the illustrative construction, I have shown the fuse carried in suitable open-ended socket members 1 and 2, which may be of any well known construction, preferably resilient, and are preferably formed 50 of conducting material and connected to the line as indicated in dotted lines in Fig. 1. In these members 1 and 2, the end members

3 and 4 are disposed, these members 3 and 4 being preferably cylindrical and formed of conducting material in the form of caps 55 adapted to make electrical contact with the sockets, and one of these members, as for instance the member 4, being connected to a fuse carrying element 5, hereinafter described, and removable therewith, while the 60 other member, as for instance the member 3, is connected to a fuse casing 6.

In my improved construction, it will be noted that this casing 6 is cylindrical in form and preferably made of insulating material having the conducting member 3 fitting over and preferably threaded on one end of the same at 7, and also preferably rigidly connected thereto as by a pin 8 in order to prevent relative rotation. At its 70 opposite end, it will be noted that this casing 6 is provided with a plurality of longitudinally extending notches 9. These notches 9 are, as shown, adapted to receive the ends of a transversely disposed pin 10 carried on the member 4, the construction of the latter preferably being such that the end of the casing 6 may extend into suitable annular grooves 11 in this member so that when the latter is moved toward the 80 casing the pin 10 may seat in the notches 9 and the member 4 thus be locked against rotation with respect to the casing 6.

As shown, the fuse carrying element is rigidly connected to the member 4 and comprises a longitudinally extending insulating base 12 of substantially semi-cylindrical cross section throughout its length and adapted to fit into and fill approximately one-half of the casing 6. As shown, the opposite ends of this base 12 are connected by any suitable means, as by screws or pins 13, 14, with inwardly projecting extensions 15, 16, respectively, on a conducting end member 17 of cylindrical cross section, slideable 95 within the casing 6, and on the member 4. Thus, it will be noted that the member 4, base 12, and member 17, are movable as one element.

Upon the movable element thus formed, is 100 carried the fusible element 18, the same preferably having slotted ends clamped by screws 19, 20 to the extensions 15, 16, and its middle portion extending upward over an

upwardly projecting extension or bridge 21 carried by the base 12 and integrally united therewith or connected thereto by suitable connecting means such as pins 22. In the 5 form of my invention shown, this portion 21 extends transversely across the casing at substantially the center thereof and likewise substantially fills one-half of the bore of the casing 6 to divide the casing into two compartments or blowing spaces, leaving only a 10 small or restricted passage 23 through which the bowed middle portion of the fusible element 18 extends, the ends of this fusible element being provided with oppositely disposed notches 24 on each side of the member 21, leaving a restricted fuse section which is more easily burned than the body of the 15 fuse.

In the use of my improved fuse, the fuse 20 carrying element comprising the members 17, 12, 21, and 4, with the fuse 18 connected thereto, is connected to the end member 3 of the casing 6 by means of a suitable removable connection including a screw or bolt 25, 25 preferably provided with a knob 26 to enable the same to be readily adjusted, and passing through a hole 27 of larger diameter in the end member 3 into engagement with a suitable threaded recess 28 in the end 30 member 17. Thus, it will be noted that by simply inserting the fuse carrying element in the casing with the pin 10 in registry with the slots 9, the casing and fuse carrying element may be rigidly connected together by 35 threading in the bolt or screw 25, and that both the fuse carrying element and the casing are thus locked securely against independent rotation.

Obviously, when it is desired to remove 40 the fuse carrying element, this may also be readily done by simply removing the bolt or screw 25, whereupon the entire fuse carrying element may be bodily withdrawn from its casing, the member 17 thereon then acting 45 automatically to clean the inner surface of the casing 6. Obviously, when the fuse carrying element has been thus withdrawn, the same will form a separate unit which may be readily handled without any danger 50 of breakage, and one in which the process of substituting a new fuse for the burned out fuse may be readily carried out by simply pulling out the severed ends of the burned out fuse and projecting the ends of the new 55 fuse under the screws 19, 20, the latter being loosened or tightened, as necessary.

In the use of my improved construction, it 60 will also be noted that, due to the provision of the extension 21 on the base 12, the chamber in which the fuse is carried is restricted at a point substantially midway between the ends of the fuse, and between the weakened portions thereof where the latter is apt to be severed, the space above the base 12 thus be-

ing divided into two compartments or blowing spaces in such a manner that the injurious effects of the burning of the fuse are thereby minimized. One of the restricted portions will blow first, heating and expanding the air in its compartment to such an extent that the section of the fuse resting on the bridge is immediately blown into the opposite compartment, and so lengthening the arc. The bridge prevents molten pieces of fuse from assisting in maintaining an arc, 70 and since the arc tends to travel in straight lines but is prevented from passing in a straight line from contact to contact by the bridge, the arcing will stop. These and other advantages of my improved construction will, however, be clearly apparent to 75 those skilled in the art.

While I have in this application specifically described one embodiment which my invention may assume in practice, it should 80 be understood that the form thereof shown herein is used only for purposes of illustration, and that the invention may be modified and embodied in other forms without departing from its spirit, it being my intention to include all such modifications within 85 the scope of the appended claims.

What I claim as new and desire to secure by Letters Patent is:—

1. In an electric fuse, a fuse casing, a 90 unitary fuse carrying element reciprocable therein, and means on one end of said element for cleaning the inner wall of said casing as the element is reciprocated therein.

2. In an electric fuse, a fuse casing, a 100 unitary fuse carrying element reciprocable therein, a fuse carried on said element, and means on said element in spaced relation to the fuse for cleaning the inner wall of said casing adjacent said fuse as said element 105 is reciprocated therein.

3. In an electric fuse, a fuse casing, a unitary fuse carrying element reciprocable therein having a cleaning portion engaging the inner periphery thereof and a portion 110 extending substantially across a part of the inside of said casing, and a fuse extending over said last mentioned portion and having downwardly extending ends connected to said element.

4. In an electric fuse, a fuse casing, a unitary fuse carrying element reciprocable therein having a cleaning portion engaging the inner periphery thereof and a transversely disposed portion forming a bridge 120 substantially filling a part of said casing, and a fuse on said element extending between said last mentioned portion and said casing.

5. In an electric fuse, a fuse casing, a 125 unitary fuse carrying element reciprocable therein, a fuse carried on one side of said element, means on said element for scrap-

ing the adjacent wall of said casing as the element is withdrawn therefrom, and means for clamping said fuse carrying element to said casing.

5 6. In an electric fuse, a casing, a fuse carrying element reciprocable therein comprising a base having one end of the same cross section as the interior of said casing and having an upstanding bridge between its 10 ends, and a fuse connected to said fuse carrying element at its opposite end and extended over said bridge.

7. In an electric fuse, a casing, a fuse carrying element reciprocable therein comprising a base of similar cross section to a portion of a transverse section of the interior of said casing and having a transversely disposed bridge thereon filling a substantial part of the remaining cross section 20 of a part of said casing, a fuse connected to said fuse carrying element and extending over said bridge, and a combined casing cleaning and conducting element connected to one end of said fuse.

25 8. In an electric fuse, a casing, a fuse carrying element reciprocable therein and comprising a base having a transversely disposed bridge thereon filling a substantial part of the cross section of said casing, a 30 fuse connected to said fuse carrying element and extending over said bridge, a cleaning member on said base slidably engaging the interior of said casing as said base is reciprocated, and means for connecting said fuse carrying element to said casing.

9. In an electric fuse, a casing, a fuse carrying element reciprocable therein and comprising a base having a transversely disposed bridge thereon filling a substantial part of the cross-section of said casing, a 40 fuse connected to said fuse carrying element and extending over said bridge, a casing cleaning member reciprocable with said base, means for connecting said fuse carrying element to said casing, and means for locking said casing and fuse carrying element against relative rotation.

10. In combination, an insulating fuse casing having a conducting end member adapted to coöperate with a socket member, a unitary fuse carrying element disposed in said casing and reciprocable therein, a fuse thereon, means on said fuse carrying element whereby said fuse may be renewed or replaced, said fuse carrying element having a conducting end member adapted to coöperate with a second socket member, and a member removable from the exterior of said casing for connecting together said casing and fuse carrying element, said fuse carrying element being constructed and arranged to expose said means whereby the fuse element may be renewed or replaced upon removal of said

member and withdrawal of said fuse carrying element from said casing.

11. In combination, a fuse casing having a conducting end member adapted to coöperate with a socket member, a fuse carrying element disposed in said casing and reciprocable therein and having a conducting end member adapted to coöperate with another socket member, a fuse on said fuse carrying element, means on said fuse carrying element whereby said fuse may be renewed or replaced, means for clamping together said fuse casing and said fuse carrying element, and means for locking said fuse casing and said fuse carrying element against relative rotation.

12. In an electric fuse, a casing having closed ends, a unitary fuse carrying element reciprocable longitudinally thereof, said element comprising a member fitting the interior of said casing, and a fuse carrying member secured to said first mentioned member and disposed within the confines thereof whereby a scraping edge is provided at the periphery of said first mentioned member.

13. In an electric fuse, a casing, a fuse carrying element reciprocable therein comprising a base of less cross sectional area than the internal area of the casing, and having a bridge member secured thereto and filling a substantial part of the remaining cross section of said casing at a point between its ends, and a fuse connected to said fuse carrying element and extending over said bridge.

14. In combination, an insulating fuse casing, a conducting member secured to one end thereof and adapted to coöperate with a socket member, a fuse carrying element reciprocable in said casing and comprising a pair of conducting members fitting snugly 100 the bore of said casing, and an intermediate fuse carrying member of less cross sectional area than said casing, one of said last mentioned conducting members being adapted to contact with the conducting member secured 105 to the end of the fuse casing, and the other thereof being provided with a concentrically arranged sleeve adapted to coöperate with a second conducting socket member.

15. In an electric fuse, a casing, a fuse carrying element reciprocable therein comprising a base of substantially semi-circular cross section, the arcuate wall of said base being disposed concentrically with the wall of said casing, a transversely disposed bridge 120 on said base filling a substantial portion of the remaining cross section of said casing but of less length than said fuse carrying element whereby spatially separated chambers are formed on opposite sides of said bridge, a fuse connected to said fuse carrying element and extending over said bridge, and a combined casing cleaning and conducting

element connected to one end of said fuse carrying element.

16. In an electric fuse, a casing, contact members disposed at the ends thereof, and 5 a fuse carrying member disposed in said casing and having a metallic scraping member normally in contact with one of said contact members.

17. In an electric fuse, a casing, contact members disposed at the ends thereof, and a 10 fuse carrying member reciprocable in said casing and having at its inner end a combined casing scraping and contact member.

In testimony whereof I affix my signature.

FRANK E. WILLEY.
